UNITED STATES PATENT OFFICE.

CLIFFORD H. RAMSEY, OF GLEN ROCK, NEW JERSEY.

MANGLE.

1,409,405.

Specification of Letters Patent. Patented Mar. 14, 1922.

Application filed January 12, 1921. Serial No. 436,688.

To all whom it may concern:

Be it known that I, CLIFFORD H. RAMSEY, a citizen of the United States, residing at Glen Rock, in the county of Bergen and 5 State of New Jersey, have invented certain new and useful Improvements in Mangles, of which the following is a specification.

This invention relates to machines for treating sheet material and particularly 10 fabrics with liquids, as sizing liquids, by passing them between rolls, called "nip rolls", one of which is made in some way to carry on its surface and to the sheet the liquid of treatment, as by contacting with a 15 pick-up roll which dips into a container for the liquid. In these machines the several rolls are held pressed against each other and the pick-up roll and adjoining nip-roll are geared together so as to rotate at the 20 same surface speed, and heretofore they have been geared together directly (by a gear on one intermeshing with a gear on the other), in consequence of which proper intermeshing of their gears endures only so long as 25 the diameter of the rolls remains in the original proper proportion to that of their gears, and if the rolls undergo reduction in diameter for any reason, as from wear or re-surfacing them, the intermeshing co- 30 action of the gears will be faulty. One object of the invention is to provide a gearing connection between the said rolls wherein a good intermeshing co-action will be maintained though the diameter of the rolls changes for 35 any reason. Another object is to provide means whereby a micrometer adjustment of the spacing of the several rolls may be effected and accurately preserved and yet the rolls left free for movement away from each 40 other for any purpose, as in introducing the goods between the nip rolls at the beginning of a treatment.

In the drawings,

Figure 1 is a side elevation of a machine, 45 known as a "quetch" and employed for treating fabrics with liquids, embracing my invention;

Figure 2 is a section on line 2—2, Figure 1;

50 Figure 3 shows the improved gearing as seen from the left in Figure 1; and

Figure 4 is a section on line 4—4, Figure 3.

55 The frame *a* of the machine includes a pair of uprights *b* and at the ends thereof suitable bearings *c* for the trunnions *d* of

the beams *e* on which the material *A* to be treated is wound. It will be understood that the material *A* comes to the machine wound on one beam *e* and upon having its free end attached to the other beam the latter is rotated by suitable means to advance the material lengthwise and wind it on said latter beam; and that after the material has thus been wound from one beam to the other the 60 operation may be reversed. *f* designates a pan or other receptacle holding the liquid of treatment, as size.

g, *h* and *i* respectively designate the pick-up roll and the lower and upper nip rolls. 70 The roll *g* is journaled in fixed bearings *j* on the frame. The rollers *h* and *i* are journaled in pairs of levers *k* fulcrumed one above the other on suitable studs *l* adjustably set in vertical slots *m* in the uprights *b*. 75 The levers *k*, which are fulcrumed between their ends, have on their said ends weights *n* which are adjusted so that the roll *h* is normally urged toward the roll *g* and the roll *i* toward the roll *h* with that pressure which 80 is requisite for causing the roll *g* to deliver liquid to the roll *h* and the rolls *h* and *i* to exert the desired compression on the material *A*, according to the nature thereof and other considerations, the limit of movement 85 of the rolls *h* and *i* in the direction in which they are thus normally urged being determined by certain micrometer adjustment means to be set forth.

o designates suitable elevatory means for 90 moving the levers *k* contrary to the direction in which they are normally urged whenever it is necessary for any reason to interrupt their pressure coaction with each other.

Roll *i* is driven by the material *A* as an 95 incident of its frictional contact with roll *h*. Roll *g* is positively driven by any suitable means (not shown). In practice it is found that the frictional contact between the rolls *g* and *h* is not sufficient to transmit rotation 100 to the roll *h* from roll *g* (at least constantly and at the same surface speed, which is desirable in order to produce an even distribution of the sizing liquid over the surface of roll *h* and hence on the fabric), and so it is 105 customary to connect these two rolls by gearing, usually consisting of two gears on the rolls *g*—*h* which intermesh when the rolls are together. Instead of such gearing I place on the rolls *g*—*h* non-intermeshing gears 110 *p*, *q* and on two levers *r*, *s*, which are fulcrumed coaxially with, as on the shafts of,

the rolls g h and are pivoted together at t , transmission gears u v , which mesh with each other and with gears p q , respectively, one of the transmission gears, u , being journaled on the stud t forming the pivot between the levers. By this arrangement in any spacing of the rolls g h the gears u v preserve constant relation to the centers of the respective gears p q and gear v preserves constant relation to the center of gear u , so that the original condition of intermesh of the gears never alters. By providing only two levers in the lever system carrying the gears u v the construction is considerably simplified, because the levers are self-supporting; if there were three or more levers in series the system would require special support to prevent its falling and so permitting gear v to mesh with both gears p q .

20 The micrometer adjustment of the spacing of the several rolls is effected and accurately preserved so as to leave the rolls free for movement away from each other when necessary, as at the beginning of a treatment when the goods is to be removed, or for changing the rolls, as follows: The structure including each lever k also includes, pivoted to the lever, the fitting w , in the form of a fork which straddles the lever and whose head w' has a flat end face and on its periphery an index w^2 . An adjustable stop for each lever structure is pivoted on the upright, the same in the present instance consisting of a nut x pivotally movable on a study y projecting from the upright and a threaded shank z which is tapped into the nut and has a handle 2 at one end for turning it and an abutment head 3 fixed thereon at a point short of its other end, which is 40 telescoped into the head w' of the corre-

sponding fitting w ; the abutment head has a dial 3' on its periphery to coact with the index w^2 . The arrangement is such that having adjusted the weights n on the levers so as to produce the desired downward pressure of the rolls i and h , their limit of downward movement (that is, the desired center to center spacing of the rolls) may be nicely determined by turning the screws z ; and since the parts w and z are telescoped to and hence guide each other the adjustment once obtained will always ensue after the levers have been moved to space the rolls for any purpose.

Having thus fully described my invention, what I claim as new and desire to secure by Letters Patent is:—

1. In a machine of the class set forth, the combination of a frame structure, a roll-supporting lever-structure fulcrumed therein and normally urged to move on its fulcrum in one direction, and an adjustable stop on one structure engageable by the other structure to limit the movement of the lever structure in said direction, and including a threaded shank and a nut thereon, said shank freely telescoping said other structure.

2. In a machine of the class set forth, the combination of a frame structure, a roll-supporting lever-structure fulcrumed therein and normally urged to move on its fulcrum in one direction, one of said structures including a pivoted fitting, and an adjustable stop pivoted on the other structure and freely telescoping the fitting and engageable thereby to limit the movement of the lever structure in said direction.

In testimony whereof I affix my signature.
CLIFFORD H. RAMSEY.
